UNITED STATES PATENT OFFICE.

JAMES S. LANG, OF BOSTON, MASSACHUSETTS.

INCANDESCENT IGNITER FOR GAS-ENGINES.

SPECIFICATION forming part of Letters Patent No. 727,158, dated May 5, 1903.

Application filed April 16, 1902; Serial No. 103,122. (No model.)

To all whom it may concern:

Be it known that I, JAMES S. LANG, a citizen of the United States, residing at Boston, in the county of Suffolk and State of Massachusetts, have invented a new and useful Improvement in Incandescent Igniters for Gas-Engines, of which the following is a full, clear, and exact description, reference being had to the accompanying drawings, forming a part of this specification, in explaining its nature.

The invention relates to gas-explosion engines; and it pertains to an improved means for permanently igniting the gaseous charge as it is successively formed in the combustion-chamber, the construction and operation of which igniter can be best seen and understood by reference to the drawings, wherein—

Figure 1 represents in vertical cross-section a portion of a gas-explosion engine fitted with the improved means of ignition. Fig. 2 shows the improved igniter in perspective.

Referring to the drawings, A is a portion of the upper part of a gas-explosion-engine case providing the combustion-chamber a. The gas is fed to the chamber through the valve-controlled supply-pipe a' in the usual manner, and the exploded charge escapes through the exhaust-port a² and pipe a³, which is valve-controlled, as is usual in engines of this kind.

After the engine has been started by a primary ignition of the gaseous charge, which may be accomplished in any suitable way, as electrically by the rocking electrode a⁴ contacting with the fixed electrode a⁵, the rocking electrode being actuated in any suitable manner, it is the purpose of my invention to provide a means superseding the primary and temporary means of ignition and furnishing a means tending to the permanent ignition of the gaseous charge as it forms successively in the combustion-chamber.

The permanent igniting device comprises a medium B, which is contained in the exhaust-port of the combustion-chamber and which is heated and kept hot by the repeated exhaust charges which pass through it, these of course being sufficiently hot to accomplish this end.

For an igniting device of this kind it is desirable to employ a metal which is refractory to high heat and yet will serve to retain heat.

It is also desirable that it should be so shaped as not to impede the outward flow of the exhaust and still present a relatively large area of incandescence, with which the compressed gas of a charge may come into contact at the desired interval and be exploded. I have therefore represented the igniter as in the form of a coil made from a flat strip of nickel, platinum, or other suitable metal, loosely wound, so as to provide a sufficient space between the coils for the outmoving exhaust, the coil being supported in the exhaust-passage so that the space between the coils is in line therewith. The outer coil preferably is covered with a layer b, of asbestos or other non-absorbent of heat, whereby heat is held in the coil and prevented from heating the wall of the exhaust-passage about it. This result may likewise be obtained by lining the exhaust-passage with some non-heat-conducting material for the length in which the igniter is movable, or, as shown in the drawings, this lining may be supplementary to the covering upon the outer coil, as aforescribed. I also prefer that the igniter be so supported in the exhaust-passage as to be movable at will toward or from the explosion-chamber, and this result is reached by suspending it from a sliding rod b², supported at one end in a manner to permit it to be moved horizontally and at the other end by a crank b³ on the lower end of a turning-rod b⁴, which extends without the case and has a handle b⁵, by which it and the crank may be turned. The movement of the crank will therefore cause the igniter to be moved toward and from the explosion-chamber as may be required.

The permanent igniter such as I have described serves, of course, as the means for igniting the gaseous charges successively formed in the combustion-chamber only when it has become sufficiently hot to accomplish this end. Inasmuch as the heating of the igniter is best accomplished by the heated exhaust-blast from the exploded charge it necessarily follows that the primary means of ignition must be employed to start the engine and temporarily until the permanent igniter is sufficiently hot to supersede it. This once accomplished the means furnishes a very

simple and effective method of permanent ignition.

I claim—

1. In an engine of the character specified a main igniter contained wholly in the exhaust-passage leading directly from the explosion-chamber and between it and the exhaust-valve, all parts of which main igniter are adapted to become heated and kept hot by the passage of the full exhaust charge past them to the exhaust-port.
2. In an engine of the character specified a main igniter entirely contained in an exhaust-passage leading directly from the explosion-chamber, which igniter divides the exhaust-passage into a plurality of passages through which the exhaust charge passes to the exhaust-port.
3. In an engine of the character specified a main igniter contained entirely in an exhaust-passage leading directly from the explosion-chamber and between it and the exhaust-valve, which igniter is adapted to become heated and kept hot by the passage of the entire exhaust charge to the exhaust-port, and means for moving said igniter lengthwise of said exhaust-passage to vary its position with regard to the explosion-chamber and to thus vary the time of the explosion.
4. In an engine of the character specified, a main igniter contained in the exhaust-passage, heated and kept hot by the exhaust, and a non-heat-absorbent covering its outer surface.
5. In an engine of the character specified, a

main igniter contained in the exhaust-passage, heated and kept hot by the exhaust, and a non-heat-conducting material lining the portion of the exhaust-passage which contains the igniter.

6. In an engine of the character specified, a main igniter contained in the exhaust-passage, heated and kept hot by the exhaust, means for adjusting it lengthwise said passage, and a non-heat-conducting material lining the passage for the length in which the igniter is movable therein.

7. In an engine of the character specified, a main igniter contained in the exhaust-passage and comprising an open coil of refractory material, adapted to be heated and kept hot by the exhaust, but not to be destroyed by heat.

8. In an engine of the character specified, a main igniter contained in the exhaust-passage, made of refractory material in the form of an open coil and arranged lengthwise the exhaust-passage with its opening between the coils in line therewith.

9. In an engine of the character specified, a main igniter contained in the exhaust-passage and attached to a sliding rod, said sliding rod, and means extending without the engine for moving said sliding rod from without the engine and also the igniter attached to it.
